UNITED STATES PATENT OFFICE.

GEORGE GOLDFOOT, OF CORK, IRELAND.

ARTIFICIAL TOOTH.

1,302,152.

Specification of Letters Patent. Patented Apr. 29, 1919.

Application filed August 24, 1916. Serial No. 116,718.

To all whom it may concern:

Be it known that I, GEORGE GOLDFOOT, L. R. C. P. E., L. R. C. S. E., L. F. P., S. G., a subject of the King of England, residing at 42 South Mall, in the city of Cork, Ireland, medical and dental practitioner, have invented certain new and useful Improvements in or Relating to Artificial Teeth, of which the following is a specification.

10 This invention relates to interchangeable teeth and backings.

According to the present invention, a portion of the vertical and lingual bases of an artificial tooth, which is provided with a vertical tube or passage, is so shaped or cut as to form a right or an acute angle, or a curve of which the tangents to the extremities thereof form a right or an acute angle to each other; the backing being shaped to fit the bases or base of the tooth and provided on its superior or upper surface with a post adapted to pass through said vertical tube or passage of the tooth.

25 I will further describe my invention with the aid of the accompanying sheet of explanatory drawings, which illustrate, by way of examples only, modes of embodying same, like characters of reference denoting like or equivalent parts wherever they occur.

30 In said drawings:—

Figures 1 and 2 illustrate in longitudinal section a porcelain tooth designated *a*, provided with a vertical tube or passage *b*, in which tooth the base and part of the lingual surface are cut away so as to form a right angle—or an acute angle as indicated by the dotted line *c*—Fig. 1; or a curve (Fig. 2) of which the tangents *d* *e* to the extremities thereof form a right or an acute angle to each other. Said tube or passage *b* may be unlined as illustrated or lined with smooth or ridged metal, and extends longitudinally through the center and body of the tooth *a*.

35 Figs. 3 and 4 illustrate metal backings generally designated *f*, which are respectively adapted to fit the teeth according to Figs. 2 and 3, being made with two surfaces which form a right or an acute angle, or a curve of which the tangents to the extremities thereof form a right or an acute angle to each other.

40 On the superior or upper surface *f* of

each of said backings *f* there is secured the lower end of a post *g* adapted to pass through the tube or passage *b* of its tooth, 55 and which post may be smooth or ridged as desired.

5 Figs. 5 and 6 and views of backings similar to Figs. 3 and 4, illustrating the provision on the lingual surface of a projection 60 or tag *h* for vulcanite work.

Having now described my invention, what I claim as new and desire to secure by Letters Patent is:—

1. An interchangeable artificial tooth 65 having a portion of the vertical and lingual bases so shaped as to form a right or an acute angle, or a curve of which the tangents to the extremities thereof form a right or an acute angle to each other, and provided with a tube or passage adapted to receive a post secured on the superior or upper surface of a backing.

2. In combination, an interchangeable artificial tooth having a portion of the vertical and lingual bases so shaped as to form a right or an acute angle, or a curve of which the tangents to the extremities thereof form a right or an acute angle to each other, and provided with a tube or passage: and a 70 metal backing formed to fit the bases or base of the tooth and provided on its superior or upper surface with a post adapted to pass through said tube or passage of the tooth. 75

3. In combination, an interchangeable artificial tooth having a portion of the vertical and lingual bases so shaped as to form a right or an acute angle, or a curve of which the tangents to the extremities thereof form a right or an acute angle to each other, and provided with a tube or passage; and a 80 metal backing formed to fit the bases or base of the tooth and provided on its superior or upper surface with a post adapted to pass through said tube or passage of the tooth 85 and on its lingual surface with a projection 90 or tag. 95

In testimony whereof I affix my signature in the presence of two witnesses.

GEORGE GOLDFOOT.
